DESIGN FOR AN AIR VALVE

Alonzo H. Magee, Westfield, N. J.

Application July 24, 1935, Serial No. 57,792

Term of patent 14 years

To all whom it may concern:

Be it known that I, Alonzo H. Magee, a citizen of the United States of America and a resident of Westfield, county of Union, State of New Jersey, have invented a new, original, and ornamental Design for Air Valves, of which the following is a specification, reference being had to the accompanying drawing, forming part thereof,

which is a perspective view of an air valve embodying my new design.

I claim:

The ornamental design for an air valve, as shown.

In testimony whereof I have signed this specification.

ALONZO H. MAGEE.
